UNITED STATES PATENT OFFICE.

RUDOLPH SATTLER, OF CINCINNATI, OHIO.

PLATE-PRINTING MACHINE.

Application filed November 3, 1923. Serial No. 672,507.

To all whom it may concern:

Be it known that I, RUDOLPH SATTLER, a citizen of the United States, residing at Cincinnati, in the county of Hamilton and State of Ohio, have invented certain new and useful Improvements in Plate-Printing Machines, of which the following is a specification.

My invention relates to printing from engraved plates, and more particularly to machines such as those disclosed and claimed in my Patents, No. 1,447,433, dated March 6, 1923, No. 1,447,434, dated March 6, 1923, and 1,447,435, dated March 6, 1923, and No. 1,497,304, dated June 10, 1924, on which my present invention is an improvement. In many respects, the present machine is the same as the one specifically claimed in the two last mentioned patents; and these two patents will be referred to herein in connection with the description of several of the details, and also are referred to as to broader claims therein for several parts of the present machine. The object of the present invention is to further increase the ease and accuracy of operation, and to provide greater strength and durability, as well as to make the machine more safe and convenient for the operator. Other objects will appear in the course of the ensuing description.

I attain these objects by the device illustrated, for example, in the accompanying drawings, in which—

Figure 1 is a plan view, certain parts being broken away to reveal underlying details;

Fig. 2 is a partial longitudinal vertical section on the plane of the line 2—2 of Fig. 1, to show the D-roller holder and bed-holding dog;

Fig. 3 is a sectional side elevation;

Fig. 4 is a detail side elevation of the meshing mechanism by which the D-roller is driven;

Fig. 5 is a side elevation showing the parts in positions different from those of Figs. 1 to 4, inclusive, and showing the clutch controller releasing device partly in section as in Fig. 3;

Fig. 6 is a detail front elevation of the manipulating means for the controller engaging mechanism;

Fig. 7 is an enlarged detail sectional view of the arch-cap clamping means.

The frame comprises the base 1, sides 2

and 3, and strut 4 of H-shaped cross-section, the latter rigidly connecting the sides 2 and 3 together about midway of their length and height. The bed 5 slides in guideways 60 in the upper parts of the sides 2 and 3, rearwardly and forwardly, and is supported by rollers 6, 7 and 8, with straight lower faces 9 on these rollers. The pressure roller 10 bears continuously from end to end up against the continuous lower bearing side of the front part 11 of the bed 5 when the latter is in rear position as in Fig. 5, affording a firm support during the actual printing operation. 70

Each frame side 2 or 3 has on its top rear pedestals 12 and front pedestals 13; and the arch-caps 14 have rear legs straddling the rear pedestals 12 with transverse pivots 15 therein, and have their front ends over the front pedestals 13, from which tension rods 16 extend up through openings in these front end parts, these rods being threaded in their upper end parts (Fig. 7). The cup-shaped nuts 17 have their bottoms 80 threaded on these rods 16 and receive loosely in their open tops the tubular lock-nuts 18 also threaded onto the rods 16. The nuts 17 and lock-nuts 18 have transverse holes in their walls, which register, receiving pins 19 to lock the two together at various adjustments up and down on the threads of the rods 16; the two nuts 17 and 18 compressing between them a spring 20 coiled around the rod 16 against the bottom of the cup of the nut 17 and the lower end of the lock-nut 18. The casing 21 surrounds the nut 17 and may be clamped to turn the nut 17 by a set screw 22; the casing having wings 23 affording finger-holds for screwing the entire device up or down on its respective rod 16. 90

Each arch-cap 14 is channeled on its lower side, receiving the ball-bearing 24 supported on top of a compression spring 24' which allows the arch-cap and bearing 24 to be adjusted up and down by the nut 17 yet always holds the bearing firmly. The spring 20 binds the two nuts 17 and 18 on the threads of the rod 16, so that, once adjusted, the bearings 24 will be held firmly. The segmental D-roller 25 is fixed on the transverse shaft 26 journaled in the ball-bearings 24 of the respective arch-caps, to rotate over the bed 5; and this shaft 26 extends to the left and has fixed on it a spur gear 27 meshing with a larger spur gear 28 turning on a 100 105 110

stud in the frame side 2 and meshing with a third spur gear 29 similarly mounted and being of the same diameter as the first gear 27 and having coaxial and turning with it 5 the pinion 30 meshing with a spur gear 31 which is of four times the diameter of this pinion 30 and turns on a stud extending in to the right from the inner wall of a housing 32 (shown only by dotted lines in Fig. 3) bolted to the side 2 down at the rear of the machine.

The cam-disk 33 is fixed on the left outer end of the main shaft 34, facing the inner side of the large gear 31 and carrying the 15 cam element 35 to coat with any one of four engaging bars 36 fixed on lugs projecting in from the gear 31, at equal intervals therearound. The axis of the cam disk 33 and shaft 34 is parallel with that of the 20 gear 31 that has these bars 36, but lies a substantial distance thereabove. The cam element 35 has the shape of a segment at each 25 end; the segmental radius at one end, however, being much smaller than the other, and the curves of the two being joined by a straight surface, while the opposite edge of the element is straight. This element is set 30 on the disk 33 with its larger end radially inward and having the point 37 thereof on the axis of the disk. The bars 36 are so set 35 on the large gear 31 that their inner corners 38 will coincide with the disk axis in passing around with the gear 31; and these bars are so uniformly inclined to the circle of rotation, and the cam element 35 is so inclined 40 and of such length, that, beginning with the inner point of this member coincident with the inner corner of one of the bars 36 and the cam element 35 inclining down to the front, a rotation of the disk 33 one complete 45 revolution over rearwardly will cause one-fourth of a revolution of the gear 31 over rearwardly; the engagement terminating as the point of the smaller outer end of the cam element 35 slides off the inner corner of the bar 36 after the entire edge, formed by the curves and straight junction part before described, has traversed in engagement with the straight face of the bar 36.

50 The main shaft 34 has bearings 39, inside of and on the base 1 of the frame; and a casing 40 is mounted between these bearings, enclosing a worm gear 41 fixed on the shaft 34 and meshing with a worm 42 therebelow, also enclosed in the casing 40 and fixed on the driving shaft 43 journaled from front to rear of the machine in bearings in this casing 40 and in the front and rear ends of the base 1. This shaft 43 extends out at 55 the rear, and the driving pulley 44 turns loosely thereon and has inside its rim, to the rear, the cone shaped surface 45 to receive the conical periphery of the clutch member 46, preferably of wood, fixed on a rotor 47 mounted on the shaft 43 by means of a spline

48 (Fig. 3) and carrying, spaced back from it, an engaging disk 49 keyed on the hub of the rotor. The rear end part of the shaft 43 is threaded, receiving the cup shaped nut 50 which encloses a spring 51 coiled around the 70 shaft 43 and compressed by this nut 50 against the rear end of the hub of the rotor 47; the nut 50 being locked by a lock-nut 52 against its rear end.

The base 1 of the frame has an extension 75 at the left of its rear end, carrying the fulcrum for a fork 53 extending to the right and straddling the hub of the rotor 47, with bearing blocks 54 against the front face of the engaging disk 49, above and below the 80 hub. The push-rod 55 extends from front to rear of the machine, sliding and rotating in bearings 56 and 57 in the front and rear ends, respectively, of the base 1 and having its rear end part loosely threaded into the 85 right hand end of the fork 53 (Fig. 1) by means of a sleeve 58 locked to the fork by a nut 59, for adjustment forwardly or rearwardly in the fork. At the front end of the 90 machine, an arm 60 is fixed on this push-rod 55 with its upper end pivoted to a connector 61 inclining up to the left (Fig. 6) and pivoted in the fork 62 of a manipulating lever 63 fulcrumed on the front of the frame and extending up to the left and terminating in 95 a knob 64. The connector 61 extends to the left past the fork 62 to engage with a lug 65 on top of the lever 63 as the lever is pushed up by a spring 66 coiled around a 100 rod 67 having its lower right end pivoted on a stud in the frame and its left end through a downwardly extending lug 68 on the lever 63, with the spring 66 compressed between this lug 68 and the pivoting head of this rod 67. A shaft 69 is journaled 105 transversely in the right hand side of the base 1, with a handle bar 70 extending down and forward from its outer end, and having its inner end next to the push rod 55 with one side provided with a recess 71; and a collar 72 is fixed on the push rod 55 just rearwardly from this recessed end, in such position that, if the shaft 69 is turned so that its recess 71 faces this collar 72, the rod 55 may slide forwardly, but otherwise the 110 unrecessed part of the shaft 69 will engage this collar and prevent forward movement of the push rod 55.

The main shaft 34 carries on its inner right end the crank 73 with a roller 74 115 against the front side of a longitudinal flange on the main lever 75 which has its fulcrum 76 in a lug extending down from the base 1, which base is slotted to allow movement of this lever. The bed 5 has depending ears 77 to the rear of the pressure roller 10, between which is pivoted a link 78 inclining down, when the bed is forward, to pivot to the upper end of the main lever 75; this arrangement being such as dis- 120

closed and claimed in my prior Patent No. 1,447,435 before mentioned, and the roller 74, by which the crank 73 swings the lever backward but can not swing the lever forward, is such as disclosed and claimed in my prior Patent No. 1,497,304, before mentioned.

The throw-out lever 79 has its fulcrum 80 in the right hand side of the base 1 and extends to the left, with an opening through which the push rod 55 extends, and the left end of this lever 79 is engaged by the lower end of the rocking lever 81 fulcrumed at 82 on a block 83 mounted on the bottom of the base 1; this block also holding an additional bearing for the push rod 55. The upper rear face of this rocking lever 81 is rounded, and is engaged by the edge of a cam plate 84 fixed on the main shaft 34 to the left of and coincident with the crank 73, so that as this cam plate 84 swings up forwardly, it pushes the upper end of the rocking lever 81 forward and the lower end thereof backward, and thus swings the throw-out lever 79 backward. A flange 85 has a hub around the push rod 55 at the rear of the throw-out lever 79, having a set screw clamping this flange to the rod 55; and the front face of this flange has a recess 86. A roller 87 is journaled on the rear side of the throw-out lever 79 to bear against this front face of this flange 85; the parts being so adjusted that when the push rod 55 is rocked over to the left by depressing the manipulating lever 63, the recess 86 registers with the roller 87, allowing the push rod to slide forward, although the throw-out lever is held back by the engagement of the cam plate 84 with the rocking lever 81.

For returning the bed 5 forwardly, a web 88 has its end fixed to the rear end of the bed at the right, inside the frame, and passes forwardly, downwardly and to the rear, around a small sheave 89 journaled on the same stud with the forward one 7 of the two rear bed-supporting rollers at that side, and then over another similar sheave 90 journaled on a stud in the rear end of the frame side 3. From here the web 88 passes vertically downward along a guide 91 extending up from the rear end of the base 1 (Fig. 5) and has its lower end fixed in an eye on the upper end of the weight rod 92 that passes down through and is guided by a foot 93 on the lower end of this guide 91. The lower end of this rod 92 carries a weight 94 with a recess in its top around the rod 92 receiving the lower end of the spring 95 coiled around the rod 92 and compressed against the bottom of the foot 93 as the weight is pulled up when the bed is approaching its rearmost position as seen in Fig. 5.

To cushion the front end of the bed travel,

a yoke 96, mounted across the rear end of the frame top with its end parts forming clips to hold the bed down in its guides, has formed in the top of its middle a horizontal rearwardly opening dash-pot 97; and the rear end of the bed 5 has a rearwardly extended arm 98 with its rear end projected upward and having fixed in it the plunger rod 99 carrying at its front end the plunger 100 to enter the dash-pot 97 in the latter part of the forward travel of the bed 5. Near its front end the dash-pot 97 has a port 101 controlled by a small check-valve 102 which admits air more freely than it allows the air to escape; thus avoiding obstruction in rearward starting, but causing some compression of air as the plunger 100 enters at ending of the forward stroke. The slight vacuum created at beginning of backward travel prevents too sudden starting and jar-ring of the stock from its position on the bed; thus contributing to this result along with the arrangement of main lever 75 and link 78 as fully described and claimed in my prior Patent No. 1,447,435; this dash-pot arrangement also being fully disclosed and claimed in my prior Patent No. 1,497,304, before mentioned.

The gearing which transmits the motion from the main shaft 34 to the D-roller 25 of course has back-lash; and as the crank 73 can drive the bed 5 backward, but could not prevent manual pushing of the bed backward, a detent is desirable to prevent this, as for instance, should the operator lean against the front end of the bed. To afford a positively positioned stop for the D-roller 25 in its raised inoperative position, a cam 103 is fixed on the shaft 26 at the right hand end of the D-roller 25, with an increase in its radius terminating in an abrupt drop 104, and a second drop 105. The detent housing 106 is pivoted on an inward extension of the pivot 15 of the adjacent arch-cap 14, with an arm 107 inclined upward and forwardly, having a roller 108 to bear on the periphery of the cam 103 and fit in the first drop 104 thereof when the D-roller is in its inoperative position. This housing 106 is open at its bottom, and a dog 109 is hung on the pivot 15 and pressed down past the bottom of the housing by a small spring 110 between it and the top of the housing. The edge part of the bed 5 has on top a lug 111 with gently inclined front and undercut rear end; and the dog 109 has a nose 112 on its rear end with front sloped up rearwardly to wedge down under the rear end of the bed lug 111 if the bed starts backward. The front edge of the bottom of the housing 106 engages under the dog 109; and as the D-roller 25 starts over forwardly, the roller 108 drops into the second drop 105 of the cam 103, upon which the housing 106 is swung up by a spring 113 around the

4
pivot 15 with one end engaged in the housing and the other in the pedestal 12; the dog 109 being raised with the housing, out of the path of the bed lug 111. This is permitted because the bed 5 starts much more slowly than does the D-roller; the dog 109 being set with some clearance from the bed lug 111 to take advantage of this differential, but being close enough to prevent any material backward travel of the bed under the circumstances described. During forward return travel of the bed 5, the dog 109 rides up the front side of the bed lug 111 and drops behind it automatically under action of its spring 110, although the roller 108 has not yet been reached by the second drop 105.

Further to insure a stationary condition of the D-roller 25 before starting, a second cam 114 is fixed on the shaft 26 to the right of the cam 103, with a recess 115 in the otherwise circular periphery. A rocker yoke 116 has a fulcrum 117 on top of the arch-cap 14 and its front end carries a roller 118 down against the periphery of this cam 114, while its rear end carries a small barrel over the rear part of the arch-cap 14, enclosing a small spring 119 between an adjusting screw 120 in the upper end of the barrel and a small plunger 121 projecting from the lower end thereof down against the top of the arch-cap 14, so that the spring yieldingly holds the roller against the cam, to enter the recess 115 when the D-roller reaches correct stopping position. Also, to prevent un-
due momentum of the D-roller, in stopping or in the initial stages of starting, a brake shoe 122 bears on the periphery of this cam 114 at the rear, and is mounted on the lower front end of a plunger 123 in the end of a barrel 124 forming part of the arch-cap 14 and having an adjusting screw 125 in its upper rear end, compressing a small spring 126 against the plunger 123.

Between the left end of the D-roller and the adjacent arch-cap 14, a third cam 127 is fixed on the shaft 26, for operating a guard comprising a bar 128 which extends across between the bed and the D-roller from the lower end of a lever 129 having its fulcrum 130 on top of the arch-cap 14 and curving back under the shaft 26 at the right of the cam 127. This lever 129 has a roller 131 bearing on the cam periphery, about half of which periphery is coaxial with the shaft 26, and the other half receding rapidly radially inwardly from the bottom (when the D-roller is up) to the top, where it is abruptly curves outward, forming a rest for the roller 131 in stationary condition, during which the guard bar 128 is back under the D-roller. As the latter starts over forward, the abrupt outward curve of the cam periphery pushes the roller 131 upward, quickly carrying the guard bar 128 forward and upward, out past the circle of travel of the descending larger

operating part of the D-roller, and forcing the hand of the operator away therefrom if not removed in time by the operator. As the D-roller returns to inoperative position, after operating, the roller 131 rides along the receding part of the cam 127, so that the guard bar swings back under the D-roller, under the action of a spring 132 coiled around the fulcrum of the lever 129, which turns in a bearing on the arch-cap 14; this spring having one end fixed in the arch-cap and the other end in a small cylindrical housing 133 fixed to the fulcrum and enclosing the spring, as seen in Fig. 1.

It will be understood that, in use, the gearing would be covered by a suitable guard, not shown; and that the machine would be mounted on a suitable stand, such as disclosed in the patents mentioned, with a motor thereon, below, at the rear, belted to the pulley 44; this motor operating continuously, but the machine being operated only when the clutch member 46 is engaged therewith under action of the spring 51. The pressure roller 10 is journaled in blocks 134 slidable up and down in slots in the frame sides 2 and 3, as adjusted by screws 135 extending up through projections on the outside of the frame, with heads and lock-nuts 136 below these projections (Fig. 5.) The usual bracket 137 under the bed 5 at the front, for holding a heater for the ink placed on the plate on top of the bed, is similar to that of the prior patents mentioned; and the bed has the tray 138 at its front end, for convenience of the operator, as in the prior Patent No. 1,497,304.

In operating the machine, after the plate has been suitably fixed on the bed and inked and the stock placed thereon as correctly located by a line drawn on the plate, and held in position only by its friction with the plate, as usual in plate-printing, while the bed 5 is at the front and the D-roller raised, as shown in Figs. 1 to 4, inclusive, the manipulating lever 63 is depressed by the operator engaging the knob 64 thereof. The cam plate 84 is holding the throw-out lever 79 back, which, engaging its roller with the flange 85 is holding the clutch member 46 away from the pulley 44; but this action of the operator rocks the push rod 55 so that the recess 86 registers with the roller 87, allowing this push rod 55 to slide forward, and with it the clutch member 46 into firm frictional contact with the rotating pulley 44, thus starting the driving shaft 43, which, through the worm 42 and worm gear 41, rotates the main shaft 34 over backwardly, swinging the main lever 75 by engagement of the roller 74 of the crank 73 therewith, and very slowly and gradually starting the bed 5 backward as the link 78 assumes a greater angle to the lever 75 and as the

crank 73 reduces its angle to this lever; the suction in the dash-pot 97 tending to retard the starting, as before alluded to.

At the same time, the cam element 35, 5 starting over backwardly with the main shaft 34 from the position best seen in Figs. 3 and 4, has its point 37 beginning to engage the uppermost one of the engaging bars 36 on the gear 31; at which stage, being substantially central of the shaft 34, the driving action on the gear 31 is almost nil; but as the rotation continues, parts of the cam element 35 farther from the center of the shaft 34 bear on the bar 36, which, having a greater 10 lineal velocity, drive the gear 31 with gradually increasing speed. The design of this cam element 35 is such that, as the gear 31 transmits its gradually increasing velocity to the D-roller 25, the latter will have its 15 surface moving at the same velocity as the upper surface of the stock when the D-roller has rotated over and downward and the stock has been carried, with the plate and bed, backward under the D-roller. It will be 20 understood that this D-roller, as fully set forth in the prior patents, and as is well known in the art, is covered with a suitable blanket or backing, held by suitable clamps 25 139 (Fig. 3) which contacts with the stock; and it is with respect to the radius of this covering that the parts are designed, so that at the instant of contact with the stock, this covering is moving at the same speed as the 30 stock, avoiding slippage of the stock on the plate. 35

As soon as the operator removed the hand from the manipulating lever 63, the spring 66 rocked the push rod 55 over to the right 40 again, until the connector 61 engaged the lug 65 of the lever 63; but during the time of this action, which is slow relative to that of the machine driving device, the cam plate 84 has left the rocking lever 81 so that there 45 is nothing to move the throw-out lever 79 backward, and the clutch member 46 will remain in contact with the pulley 44.

The printing operation then progresses, 50 with the bed 5 traveling backward and the D-roller rotating under and upward to the rear until the parts are in the positions shown in Fig. 5 with the crank 73 at right angles to the lever 75 and ready to recede therefrom as it continues to rotate under 55 and forwardly. The bed 5 has pulled the weight 94 up until the latter has compressed the spring 95 as seen in Fig. 5, cushioning the travel of the bed so that the latter stops at this point, having gradually become 60 slower by the crank and lever action, without jar. Now, the weight 94 will pull the bed 5 forward, independently of the action of the main lever 75, until stopped gradually by the dash-pot 97 as before described. 65

As seen in Fig. 5, the cam element 35 still is acting upon the bar 36; beginning to carry its small curved end across this bar downward, during which it will slightly further turn the gear 31 and the D-roller 25 there-with, until the latter reaches its uppermost 70 stationary position again, soon after the beginning of return of the bed 5. It will be seen that this final turning of the D-roller will be very slow; and with the assistance of the brake device 122, and the rollers 108 75 80 and 118 in the cam parts 104, 115, the D-roller is stopped without jar, accurately in its correct position for starting again at the next printing operation. In some cases, the first drop 104 of the cam 103 may be omitted, 85 using this cam 103 only for operating the dog 109 as before described, and depending upon the roller 118 in the recess of the cam 114 to insure the correct stopping of the D-roller. This especially is permissible in conjunction with the brake device 122 which overcomes any tendency of the D-roller to continue backward and overcome the action of the stopping roller 118 alone.

At the next operation, since the gear 31 90 rotates only one-fourth turn to one of the D-roller, and the engagement of the cam element 35 and bar 36 is such as to provide exactly this one-fourth revolution of the gear 31, the point 37, centrally of the driving shaft 34, will be at the inner corner of the next bar 36 of the gear 31, over forwardly; the close approach of this point 37 to this corner being seen in Fig. 5. These parts thus are in positions to cause the very 95 gradual starting of the D-roller again at this next operation.

The cam plate 84, at ending of the complete revolution of the shaft 34 and crank 73, engages the rocking lever 81, swinging the throw-out lever 79 backward, and, as the recess 86 was rocked away from the roller 87 as soon as the operator released the manipulating lever 63, this throw-out lever pushes the push rod 55 backward, which 100 pushes the clutch member 46 away from the pulley 44, disconnecting the motor from the machine.

If it is desired to prevent operation of the machine, as while the operator is making 115 adjustments of the plate or the D-roller covering while the motor is running, or as when leaving the machine unattended without stopping the motor, the handle bar 70 is swung up forwardly, bringing the unrecessed part of the shaft 69 against the collar 72. This device is in convenient reach of the operator, who may use it at any time, and may throw it off to permit starting, with ease. It is especially useful where, as 120 is the practice, the skilled operator inks the plate and supervises the operation of the machine, and a less skilled helper places the stock on the plate ready for accurate setting by the printer, and then depresses the ma- 125 130

6
nipulating lever 63 for the printer as soon as the latter is ready for the machine to be started. Thus, the printer may protect the work against mistaken action of the helper 5 at any time the situation seems to demand such precaution. With the bar 70 downward the lever 63 can be depressed, but no further action can occur.

The casing 21 is removed from the nut 17 10 if it is desired to change the pressure of the binding spring 20; this permitting the pin 19 to be removed endwise and the lock-nut 18 screwed up or down; the holes in the walls of the latter being elongated up and 15 down to permit this, and the adjustment of course always being such that the holes in the two nuts 17 and 18 register, and amounting, therefore, to one or more half revolutions of the nut 18 relatively to the nut 17. 20 The various details of the invention have been somewhat specifically described, to make clear the construction and use thereof, as is required, but I do not wish to be understood as being limited to such precise 25 showing and description, but having thus fully described my invention, what I claim as new and desire to secure by Letters Patent is:

1. In a machine of the character described, in combination with a bed having a printing movement and a return movement, pressing means, and mechanism for causing one of said movements of said bed, a cam element actuated by said mechanism, and an operative connection to said pressing means, engaged by said cam for causing said pressing means to press stock on said bed during part of said printing movement.

2. In a machine of the character described, in combination with a bed having a printing movement and a return movement, rotary segmental pressing means, and mechanism for causing one of said movements of said bed, a cam element actuated by said mechanism, and an operative connection to said pressing means comprising a rotary series of engaging elements engaged successively by said cam for rotation of said series through successive fractions 45 of a revolution at each printing and return movement of the bed, said operative connection being so related to said pressing means as to cause a complete revolution of said pressing means for each fraction of a revolution of said series of engaging elements, and thereby causing said pressing means to press stock on said bed during part of each printing movement thereof.

3. In a machine of the character described, in combination with a bed having a printing movement and a return movement, rotary segmental pressing means, and mechanism for causing one of said movements of said bed, a cam element actuated 60 by said mechanism, swinging around an axis,

and an operative connection to said pressing means comprising a rotary series of engaging elements arranged and rotatable around an axis displaced from but substantially parallel with the axis of swinging of said cam element, engaged successively by said cam for rotation of said series through successive fractions of a revolution at each printing and return movement of the bed, said operative connection being so related to 70 said pressing means as to cause a complete revolution of said pressing means for each fraction of a revolution of said series of engaging elements, and thereby causing said pressing means to press stock on said bed during part of each printing movement.

4. In a machine of the character described, in combination with a bed having a printing movement and a return movement, rotary segmental pressing means, and mechanism for causing one of said movements of said bed, a cam element actuated by said mechanism, swinging around an axis and having an engaging surface with one end substantially coinciding with said axis, and an operative connection to said pressing means comprising a rotary series of engaging elements arranged and rotatable around an axis displaced from but substantially parallel with the axis of swinging of said cam element, engaged successively by said cam for rotation of said series through successive fractions of a revolution at each printing and return movement of said bed, said operative connection being so related to 90 said pressing means as to cause a complete revolution of said pressing means for each fraction of a revolution of said series of engaging elements, and thereby causing said pressing means to press stock on said bed during part of each printing movement.

5. In a machine of the character described, in combination with a bed having a printing movement and a return movement, rotary segmental pressing means, and mechanism for causing one of said movements of said bed, a cam element actuated by said mechanism, swinging around an axis and having an engaging surface with one end substantially coinciding with said axis, and an operative connection to said pressing means comprising a rotary series of engaging elements arranged and rotatable around an axis displaced from but substantially parallel with the axis of swinging of said cam element, engaged successively by said cam for rotation of said series through successive fractions of a revolution at each printing and return movement of said bed, said operative connection being so related to said pressing means as to cause a complete revolution of said pressing means for each fraction of a revolution of said series of engaging elements, and thereby causing said pressing means to press stock on said bed during part of each printing movement.

thereby causing said pressing means to press stock on said bed during part of each printing movement, said surface of said cam element having a curved region to roll from its said end along each engaging element to drive said pressing means at a gradually increasing speed.

6. In a machine of the character described, in combination with a bed, rotary segmental 10 pressing means, and mechanism for moving said bed, a swinging cam element actuated by this mechanism, having an engaging surface with one end substantially coinciding with its axis of swinging, and an operative 15 connection to said pressing means comprising a rotary series of engaging elements arranged around an axis of rotation displaced from but substantially parallel with the axis of swinging of said cam element, engaged successively 20 by said cam surface for rotation of said series through successive fractions of a revolution at each movement of the bed, and so related to said pressing means as to cause a complete revolution thereof for each fraction 25 of a revolution of said series, to press stock on said bed during each movement thereof, said surface of said cam element having a curved region to roll from its said end along each engaging element to drive said pressing 30 means at a gradually increasing speed, and having an extension receding from said curved region to slide along each engaging element, gradually reducing the speed of said pressing means, finally having the opposite 35 end of the cam element leaving the initially engaging end of each engaging element.

7. In a machine of the character described, in combination with a bed, rotary segmental 40 pressing means, and mechanism for moving said bed, a swinging cam element actuated by this mechanism, having an engaging surface with one end substantially coinciding with its axis of swinging, and an operative 45 connection to said pressing means comprising a rotary series of engaging elements arranged around an axis of rotation displaced from but substantially parallel with the axis of swinging of said cam element, engaged successively 50 by said cam surface for rotation of said series through successive fractions of a revolution at each movement of said bed, and so related to said pressing means as to cause a complete revolution thereof for each fraction 55 of a revolution of said series, to press stock on said bed at each movement thereof, said surface of said cam element having a curved region to roll from its said end along each engaging element to drive said pressing means at a gradually increasing 60 speed, and having an extension receding from said curved region to slide along each engaging element, gradually reducing the speed of said pressing means, finally having the opposite 65 end of the cam element leaving the initially engaging end of each engaging element, whereupon the first mentioned end of the cam element is approached to the initially engaging end of the next engaging element of the series, for rotation of said pressing means during the next printing and return movement of the bed.

the initially engaging end of each engaging element, whereupon the first mentioned end of the cam element surface is approached to the initially engaging end of the next engaging element of the series, for rotation of said pressing means during the next movement of the bed.

8. In a machine of the character described, in combination with a bed having a printing movement and a return movement, pressing 70 means, and mechanism for causing said pressing means to press stock on said bed during part of said printing movement, a crank, a cam element swinging with said crank, said mechanism comprising engaging 75 means engaged by said cam element for operating said mechanism to cause said pressing means to press said stock on said bed, engaging means whereby said crank drives said bed in printing movement but not in return 80 movement, and means for causing said return movement.

9. In a machine of the character described, in combination with a bed having a printing movement and a return movement, pressing 90 means, a crank, a lever connected to said bed having a bearing whereby said crank drives said bed in printing movement but not in return movement, means for causing said return movement, a cam element swinging 95 with said crank, having an engaging surface with one end substantially coinciding with the axis of swinging, an operative connection to said pressing means comprising a rotary series of engaging elements arranged around 100 an axis of rotation displaced from but substantially parallel with said axis of said cam element, engaged successively by said cam surface for rotation of said series through 105 successive fractions of a revolution at each printing and return movement of said bed, and so related to said pressing means as to operate this means through a complete cycle of its operation for each fraction of a revolution 110 of said series, to press stock on said bed during a part of each printing movement of said bed, said surface of said cam element having a curved region to roll from its said end along each engaging element to drive said pressing means at a gradually increasing 115 speed, and having an extension receding from said curved region to slide along each engaging element, gradually reducing the speed of said pressing means, finally having the opposite end of the cam element leaving the initially engaging end of each engaging element, whereupon the first mentioned end of the cam element is approached to the initially engaging end of the next engaging element of the series, for rotation of said pressing means during the next printing and return movement of the bed.

10. In a machine of the character described, in combination with a bed having 120 a printing movement and a return move- 125

- ment, pressing means, mechanism for causing one of said movements of said bed, a cam element actuated by said mechanism, an operative connection to said pressing means, 5 engaged by said cam for causing said pressing means to press stock on said bed during a part of said printing movement and for moving said pressing means away from said bed, and holding means engaging directly with said pressing means to hold said pressing means away from said bed independently of action of said operative connection.
11. In a machine of the character described, in combination with a bed having a printing movement and a return movement, rotary segmental pressing means, mechanism for causing one of said movements of said bed, a cam element actuated by said mechanism, an operative connection to said pressing means comprising a rotary series of engaging elements engaged successively by said cam for rotation of said series through successive fractions of a revolution at each 25 printing and return movement of the bed, said operative connection being so related to said pressing means as to cause a complete revolution of said pressing means for each fraction of a revolution of said series 30 of engaging elements, causing said pressing means to press stock on said bed during part of each printing movement thereof and then to move away from the bed, said pressing means having a rotary part with a peripheral depression, and holding means engaging in said depression to hold said pressing means away from said bed independently of action of said operative connection.
12. In a machine of the character described, in combination with a bed having a printing movement and a return movement, rotary segmental pressing means, mechanism for causing one of said movements of said bed, a cam element actuated by said mechanism, an operative connection to said pressing means, engaged by said cam for causing said pressing means to press stock on said bed during part of said printing movement, said pressing means having a concentric peripheral part, and holding means bearing frictionally on said peripheral part to control the action of said pressing means independently of action of said operative connection.
13. In a machine of the character described, in combination with a bed having a printing movement and a return movement, rotary segmental pressing means, mechanism for causing one of said movements of said bed, a cam element actuated by said mechanism, an operative connection to said pressing means, engaged by said cam for causing said pressing means to press stock on said bed during part of said printing movement, said pressing means having a

concentric peripheral part with a depression therein, holding means engaging in said depression to hold said pressing means away from said bed independently of action of said operative connection, and holding means bearing frictionally on said peripheral part to control rotation of said pressing means during entrance of the other holding means into said depression.

14. In a machine of the character described, in combination with a bed having a printing movement and a return movement, rotary segmental pressing means, and mechanism for causing one of said movements of said bed, a cam element actuated by said mechanism, and an operative connection to said pressing means comprising gearing, one element of which has a concentric series of engaging elements engaged successively by said cam for rotation of said gearing element through successive fractions of a revolution at each printing and return movement of said bed, the ratio of said gearing being so proportioned to the number of said engaging elements as to cause a complete revolution of said pressing means for each fraction of a revolution of said gearing element, causing said pressing means to press stock on said bed during part of each printing movement thereof.

15. In a machine of the character described, in combination with a bed having a printing movement and a return movement, pressing means, and mechanism for causing one of said movements of said bed, a cam element actuated by said mechanism, an operative connection to said pressing means, engaged by said cam element for causing said pressing means to press stock on said bed during part of said printing movement, a clutch controlling operation of said mechanism, an element holding said clutch to prevent said operation, and means whereby said mechanism actuates said holding element at the end of return movement of the bed, to release said clutch, stopping said operation.

16. In a machine of the character described, in combination with a bed having a printing movement and a return movement, pressing means, and mechanism for causing one of said movements of said bed, a cam element actuated by said mechanism, an operative connection to said pressing means, engaged by said cam element for causing said pressing means to press stock on said bed during part of said printing movement, a clutch controlling operation of said mechanism, an element holding said clutch to prevent said operation, a slidtable and rotatable rod connected to this element and having a part with a recess therein, and a lever having a part to enter said recess when the rod is rotated, to allow action of said clutch to cause said operation,

and means whereby said mechanism actuates said lever at the end of return movement of the bed to release said clutch and stop said operation.

5 17. In a machine of the character described, a clutch to control operation of part of said machine, an element holding said clutch to prevent said operation, a slideable and rotatable rod connected to this element and having a part with a recess therein, a lever having a part to enter said recess to allow sliding of the rod and thereby allow action of the clutch to cause said operation, means whereby said machine actuates said lever to release said clutch and stop the operation, and means engageable with a part of said rod to prevent sliding of the rod when rotated.

20 18. In a machine of the character described, in combination with a bed having a printing movement and a return movement, pressing means, and mechanism causing said pressing means to press stock on said bed during part of the printing movement, a crank, engaging means whereby said crank drives said bed in printing movement but not in return movement, means causing said return movement, a clutch controlling operation of said crank, an element holding said clutch to prevent said operation, and means rotating with said crank which actuates said holding element at the end of return movement of the bed, to release the clutch and stop the operation of said crank.

25 19. In a machine of the character described, a crank to operate part of said machine, a clutch to control operation of said crank, an element holding said clutch to prevent said operation, a slideable and rotatable rod connected to this element and having a part with a recess therein, a lever having a part to enter said recess when the rod is rotated, thereby permitting said rod to slide and permit action of said clutch to cause said operation of said crank, and means rotating with said crank which actuates said lever to slide said rod and release said clutch to stop the operation of said crank.

30 20. In a machine of the character described, in combination with a bed having a printing movement and a return movement, pressing means, and mechanism causing said pressing means to press stock on said bed during part of said printing movement, a crank, engaging means whereby said crank drives said bed in printing movement but not in return movement, means for causing said return movement, a worm wheel turning with said crank, a worm meshing with said worm wheel, a clutch element turning with said worm and slideable axially relatively thereto, a pulley turning coaxially with said worm, contacted by said clutch

element to cause the worm to turn with the pulley, and means for sliding this clutch element.

21. In a machine of the character described, a reciprocating bed, mechanism to cause reciprocation of said bed in one direction, a clutch to control operation of this mechanism, a slideable and rotatable rod running under said bed, a connection from said rod to said clutch at one end of said bed, whereby said rod controls said clutch by sliding, means whereby sliding of said rod is controlled by rotation of said rod, and means for rotating said rod, extending past said bed near the opposite end thereof.

22. In a machine of the character described, a reciprocating bed, mechanism to cause reciprocation of said bed in one direction, a clutch to control operation of said mechanism, a slideable and rotatable rod running under said bed, a connection from said rod to said clutch at one end of said bed, whereby said rod controls said clutch by sliding, means whereby sliding of said rod is controlled by rotation of said rod, an arm fixed on said rod near the opposite end of said bed, a manipulating member extending past one side of the bed, and a connector from said arm to said manipulating member.

23. In a machine of the character described, a reciprocating bed, mechanism to cause reciprocation of said bed in one direction, a clutch to control operation of said mechanism, a slideable and rotatable rod running under said bed, a connection from said rod to said clutch at one end of said bed, whereby said rod controls said clutch by sliding, means whereby sliding of said rod is controlled by rotation of said rod, an arm fixed on said rod near the opposite end of the bed, a manipulating member extending past one side of the bed, a connector from said arm to said manipulating member, said connector being engaged by said manipulating member beyond said arm from its connection to said member, and a spring maintaining this engagement and holding said rod whereby said clutch is held to prevent operation of said mechanism.

24. In a machine of the character described, a clutch to control operation of part of said machine, an element to hold said clutch to prevent said operation, and a rod connected to said element, slideable to control said element and rotatable to control sliding of the rod.

25. In a machine of the character described, a bed, pressing means, and mechanism to actuate said bed and pressing means, comprising a rotatable element connected to said pressing means to operate said pressing means a certain number of times for each revolution of said rotatable element, an equal number of engaging elements ar-

ranged at equal intervals around said rotatable element, and a cam element revolving around an axis parallel with but displaced from the axis of said rotatable element and engaging with successive engaging elements to rotate said rotatable element through one of said intervals at each complete revolution of said cam element.

26. In a machine of the character described, a bed, pressing means, and mechanism to actuate said bed and pressing means, comprising a rotatable element connected to said pressing means to operate said pressing means a certain number of times for each revolution of said rotatable element, an equal number of engaging elements arranged at equal intervals around said rotatable element, a cam element revolving around an axis parallel with but displaced from the axis of said rotatable element and engaging with successive engaging elements to rotate said rotatable element through one of said intervals at each complete revolution of said cam element, a lever and a link connecting said lever to said bed to move said bed at a gradually increasing speed, a crank operatively related to said lever to swing said lever at a gradually increasing speed, and means whereby said cam and said crank are rotated simultaneously.

27. In a machine of the character described, a bed, pressing means, and mechanism to actuate said bed and said pressing means, comprising a rotatable element connected to said pressing means to operate said pressing means a certain number of times for each revolution of said rotatable element, an equal number of engaging elements arranged at equal intervals around said rotatable element, each having a straight side inclined at a substantial angle to a circle of revolution thereof away from the direction of revolution outwardly, a cam element revolving around an axis parallel with but displaced from the axis of the rotatable element, said engaging elements having the inner ends of their straight sides passing in substantial coincidence with the axis of said cam element and said cam element having one end substantially coinciding with said axis and having a surface to engage with said straight sides of said engaging element, this surface having a curved region to roll from the inner ends of the cam element and the respective engaging element along the straight side of the engaging element, to drive said pressing means at a gradually increasing speed at the beginning of its operation, by revolving said rotatable element through one of said intervals, said cam element having an extension receding from said curved region, to slide along the engaging element, gradually reducing the speed of said pressing means

in the latter part of its operation, finally having the opposite end of the cam element passing off of the initially engaging end of the engaging element, stopping the operation of the pressing means, whereupon the first mentioned end of the cam element is approached to the initially engaging end of the next engaging element of the series, for repeated operation of said pressing means.

28. In a machine of the character described, a reciprocating bed, a crank operatively related to said bed to reciprocate the bed, rotary pressing means to cooperate with the bed, and a cam turning with said crank and operatively related to said pressing means to rotate said pressing means while the bed is moved in one direction.

29. In a machine of the character described, a reciprocating bed, a crank operatively related to said bed to reciprocate said bed, rotary pressing means to cooperate with said bed, a gear to rotate the pressing means, having a lower number of revolutions per unit of time than the pressing means and having a number of engaging elements concentrically arranged thereon at equal intervals, the number of elements equaling the numerical ratio of the gear rotation to the pressing means rotation, and a cam turned with said crank on an axis parallel with but displaced from the axis of said gear, engaging successive ones of said engaging elements to rotate the gear through successive ones of said intervals, having a rolling contact with each engaging element to start the pressing means gradually, and then a sliding contact with the engaging element to gradually reduce the speed of the pressing means, each engaging element being so arranged that upon disengagement of the cam from one of these elements the succeeding element is in position for engagement of the cam for repeated operation as hereinbefore described.

30. In a machine of the character described, a clutch to control operation of the machine, a rod slideable to operate the clutch and also being rotatable and having a face presented lengthwise in the direction of sliding of the rod to operate the clutch for starting the machine, with a recess in said face, a movable member having a part to bear against said face to prevent machine-starting movement of the clutch but to be received in said recess upon rotation of the rod, permitting sliding of the rod to cause machine-starting movement of the clutch, and means actuated in said machine to move said movable member toward said face and slide said rod, when said part of said member is out of said recess, to cause machine-stopping movement of the clutch.

31. In a machine of the character described, in combination with rotary pressing

means and a frame, an arch element movable on the frame to adjust the pressing means to its work, a spring resisting movement of the arch element in one direction, 5 a tension element on said frame adjacent to said arch element, a cup-shaped nut threaded on said tension element bearing against the arch element in opposition to said spring, a tubular lock-nut threaded on the 10 tension element beyond the cup-shaped nut from the arch element and fitting loosely in the cup-shaped nut, a member extending across both nuts holding the nuts from rotation, a spring between the nuts, around the tension element, and a casing detachably 15 secured around the cup-shaped nut, holding said member against endwise displacement from its position across the nuts, said casing having a finger hold on its exterior, to be engaged for turning said casing and 20 the nuts therein together, for movement of said arch element.

RUDOLPH SATTLER.
